COUPLER DEVICE

Edmund P. Kinne, Alliance, Ohio, assignor to
American Steel Foundries, Chicago, Ill., a cor-
poration of New Jersey

Application November 6, 1939, Serial No. 302,963

10 Claims. (Cl. 213—153)

My invention relates to an attachment for use on automatic car couplers of standard A. A. R. type, more particularly the so-called type D and type E couplers.

Under certain unusual conditions, couplers of the present standard types have been known to uncouple accidentally due to the relative vertical movement of the two couplers involved. Such accidental uncouplings are likely to result in considerable damage owing, for example, to the emergency application of the air brakes resulting from such accidental uncoupling. Moreover, in case of derailment couplers have been known to separate under conditions when it would have been highly desirable for them to remain coupled, thus reducing the damage resulting from the derailment.

An object of my invention is to prevent accidental uncouplings due to relative vertical movement of the couplers involved.

A different object of my invention is to devise such an arrangement between mated couplers which will prevent their vertical disengagement and which will, at the same time, permit the couplers to perform their normal coupling functions including lateral and vertical angling with respect to each other.

My invention contemplates an arrangement which will permit the proper clearance conditions between coupled couplers while, at the same time, affording the flexibility which is highly desirable under normal operating conditions.

My invention comprehends such an arrangement as that above described which may be applied to all standard couplers at present in use as well as to new couplers.

Figure 1 is a front elevation of an A. A. R. standard type E coupler embodying my invention.

Figure 2 is a side elevation thereof.

Figure 3 is a top plan view of two couplers in coupled position, each embodying my invention.

Figure 4 shows in full lines a bottom plan of a coupler embodying my invention, and in phantom lines a fragmentary portion of a mated coupler also embodying my invention in lateral angling relationship.

Figure 5 is a vertical sectional view taken substantially in the longitudinal plane indicated by the line 5—5 of Figure 3, illustrating the manner in which my novel attachment limits vertical movement between coupled couplers.

Figure 6 is a further sectional view substantially in the same plane as that shown in Fig-

ure 5 but illustrating vertical angling between the mated couplers embodying my invention when there is no vertical displacement therebetween.

Describing my novel structure in greater detail and referring particularly to Figures 1 and 2, the coupler 2 is of top operating type with the lifter 3 and comprises the guard arm 4 and opposed thereto the knuckle 6 pivotally supported as at 8 by the elongated pivot pin 10, 10 said pin extending through the top and bottom ears 12 and 14 formed on the coupler head for support of the knuckle. In the front face of the coupler is the opening 16 receiving the tail of the knuckle in the usual manner. The outboard side of the guard arm is cored out as at 20 and 22 to form the usual openings therein spaced by the horizontal rib 24, thus reducing the weight of the guard arm while maintaining a structure of sufficient strength to meet the standard tests.

My novel guard attachment is in the form of a bent arm 26 having the horizontal portion 28 of triangular section (Figure 2) with the flat top at 30 forming a seat upon which the knuckle 25 of a mated coupler may ride as hereafter more particularly described. The member 26 also comprises a substantially vertical portion 32 having the hook end 34 which may be seated in the opening 22 in the side of the guard arm. The 30 hook end 34 is formed with the lug 36 which may have bearing as at 38 (Figure 2) to prevent play of the hook-like end 34 in the opening 22. The opposite end portion 40 of the member 26 is in the form of an eye having the vertical 35 opening 41 which may be aligned with the pin opening in the ears 12 and 14 and thus may receive the projecting end of the pivot pin 10. Between the ear 14 and the eye 40 may be seated the compression spring 42, and the member 26 40 may be secured in position by the castle nut 44 and the safety cotter 46, said nut 44 being threaded on the end of the pivot pin 10 to the point where the member 26 is in proper position.

With the parts assembled as shown in Figures 1 and 2, the compression spring 42 maintains the eye end 40 of the guard member 26 in proper spaced relation to afford limited relative vertical movement between mated couplers before the safety member 26 comes into operation by serving as a seat for the knuckle of the mated coupler. The range of relative vertical movement permitted between mated couplers may thus be controlled as desired. The spring 42 together with the force of gravity operating upon the 55

guard member 26 will serve to retain said member in its normal assembled relationship with the hook end 34 locked in the opening 22 on the outer side of the guard arm. The spring 42 also 5 reduces rattling and wear of the parts.

Figure 3 affords a top plan view of mated couplers embodying our invention and shows the manner in which the safety arm 26 underlies the knuckle of the mated coupler in each case. Figure 3 shows the couplers under draft with the maximum spacing indicated at M and M' between the knuckles and the faces of the opposed couplers. Under such draft conditions, it will be apparent that the safety arm 26 in each case 10 underlies a substantial portion of the mated knuckle so that it may properly function. In this view is also clearly shown the contour of the safety member 26 so formed that clearance is provided between the safety arms of mating 15 knuckles as best seen at 48, 48. In other words, when two couplers are in buffering position the spaces shown at M and M' (Figure 3) will be 20 tightly closed and the adjacent contours of the safety members 26, 26 will be in close proximity 25 with each other instead of spaced apart as seen at 48, 48 (Figure 3).

Figure 4 shows the condition when couplers embodying my invention are under maximum lateral angling with respect to each other. The 30 view is in bottom plan so that the member 26 appears in bottom elevation. In this view, the mating coupler is shown in phantom lines at 2A, and it may be noted that the safety member 26A thereof underlies a substantial part of the nose 35 of the knuckle 6 as indicated at 50.

The sectional view of Figure 5 shows two mated couplers vertically offset to the maximum permitted by my novel safety member. The coupler at the right of this view is in elevated position 40 with respect to the coupler at the left thereof so that the bottom face of the knuckle 6 of the coupler at the left is seated as at 52 upon the top face of the safety member 26 of the coupler at the right.

45 It may be noted that the distance between the bottom face of the knuckle of the right coupler is spaced above the top face of the safety member 26 of the left coupler a maximum distance indicated at X, the said distance indicating the 50 vertical range permitted by my novel safety device in the modification illustrated.

The sectional view of Figure 6 shows two couplers on substantially the same level but angled vertically with respect to each other so 55 that the respective knuckles are in abutment at their upper inner edges as indicated at 54. In other words, the tail of the coupler at the left is angled downwardly with respect to the coupler at the right, a condition which may be found in 60 hump yards for example. Under such conditions, the safety members 26, 26 of the mating couplers may abut each other as at 56. A certain flexibility is afforded in the attachment of each safety member 26, and this flexibility is best 65 understood from a consideration of the views of Figures 2 and 6. In Figure 2, it may be noted that the pivot pin 10 is centrally positioned in the opening 41 in the eye end 40 of the safety member. It may be noted that the pin opening 70 41 is tapered from top to bottom along the diameter indicated at A-B (Figure 4) so that the diameter of said opening is a maximum as indicated at 60 at the bottom and a minimum diameter at the top thereof. When a condition 75 is encountered such as is shown in Figure 6, the

safety member 26 may be pushed to one side so that the clearance of the pin 10 in the eye opening 41 will be at one side thereof as indicated at 58 in Figure 6.

The compression spring 42 serves the further useful purpose in that its application under initial compression serves to permit variations in the overall height of the coupler head between the coupler ears 12 and 14 at the top and bottom thereof, thus compensating for manufacturing 10 tolerances or wearing conditions. At the same time, it may be noted that under standard conditions the pivot pin 10 is afforded a clearance of approximately one-eighth of an inch in the pivot holes of the ears 12 and 14 so that the knuckle 15 will bear upon the pulling lugs provided around said ears instead of upon the pivot pin. As a result, the pivot pin may have a small amount of play and the safety device 26 may thus be afforded a degree of flexibility which will permit it 20 to follow the movement of the pivot pin to which it is attached.

From the above, it will be seen that I have devised a novel safety arrangement which will limit the relative vertical movement between coupled 25 couplers of standard types. As contemplated, my safety device may be modified within limits to afford reasonable vertical adjustment to permit the maximum relative vertical play between couplers that may be accommodated with safety. 30

It is to be understood that I do not wish to be limited by the exact embodiment of my invention which is merely by way of illustration and not limitation as various and other forms of the device will of course be apparent to those skilled 35 in the art without departing from the spirit of the invention or the scope of the claims.

I claim:

1. In a car coupler, a coupler head having a guard arm with an opening therein, a transversely spaced pivot pin opposite said guard arm, a knuckle pivoted thereon, a safety device connected at one end to said pivot pin and having at its opposite end a hook-like member received in said opening, and resilient means between said coupler head and said safety device adjacent said pivot point, said safety device having a horizontal portion affording a seat for the knuckle of a mating coupler to limit the relative vertical movement of said couplers. 50

2. In a car coupler, a head having a guard arm, transversely spaced pivot means opposite said guard arm, and a rigid safety device connected at one end to said guard arm and at the opposite end to said pivot means and having a horizontal portion affording stop means for the knuckle of a mating coupler to limit the relative vertical movement between said couplers, the connection of said device at its opposite ends affording limited rocking movement thereof, and resilient stabilizing means interposed between said head and said device. 55

3. In an automatic car coupling, mated couplers, each of said couplers having a guard arm and transversely spaced pivot means opposite said guard arm, a rigid safety device connected between said guard arm and said pivot means with stop means for the knuckle of a mating coupler whereby one of said stop means limits relative vertical movement between said 70 couplers in one direction and the other thereof limits said movement in the reverse direction, and a stabilizing resilient member interposed between each of said couplers and the associated device. 75

4. In a car coupler, a guard arm, a knuckle pivoted opposite said guard arm through the medium of an elongated transversely spaced pivot pin, a safety device connected at one end of said pivot pin and having a hook-like end connected to said guard arm, said device having a horizontal portion affording a seat for the knuckle of a mating coupler to limit relative motion therebetween, and a resilient member interposed between said coupler head and an end of said safety device.
5. In a car coupler, a head having a guard arm, transversely spaced pivot means opposite said guard arm, and a rigid safety device connected at one end to said guard arm and at the opposite end to said pivot means and having a horizontal portion affording stop means for the knuckle of a mating coupler to limit the relative vertical movement between said couplers, the connection of said device at its opposite ends affording limited rocking movement thereof, and a resilient member surrounding said pin and interposed between said coupler head and the adjacent end of said device.
10. In an automatic car coupling, mated couplers, each of said couplers having a guard arm, transversely spaced pivot means opposite said guard arm, and a rigid safety device connected between said guard arm and said pivot means with a horizontal portion affording stop means for the knuckle of a mating coupler whereby one of said stop means limits relative vertical movement between said couplers in one direction and the other thereof limits said movement in the reverse direction, the connection of said device at its opposite ends affording limited rocking movement thereof, and a resilient member interposed between said coupler head and an end of said device.
15. In a car coupler, a coupler head having a guard arm, transversely spaced pivot means opposite said guard arm, a knuckle pivoted thereon, a rigid safety device connected at one end to said guard arm and secured at its opposite end to said pivot means, and a resilient member under compression between said coupler head and said safety device adjacent said pivot means, said safety device having means underlying the normal position of the knuckle of a mated coupler, the connections of said device at its opposite ends affording limited rocking movement thereof and comprising an opening at one end for said pivot means, said opening having at opposite sides along one diameter thereof tapered walls serving to limit said rocking movement.
20. In a coupler, a head having a guard arm and transversely spaced pivot means opposite said guard arm, a spring mounted on said pivot means, and a safety device having an end secured on said pivot means in abutment with said spring and an opposite end connected to said guard arm, the connections between said device and said pivot means and guard arm affording limited rocking movement of said device thereon.
25. In a car coupler, a head having a guard arm, an elongated transversely spaced pivot pin opposite said arm, and a safety device secured at one end to said guard arm and at its opposite end to said pivot pin, said device having a contour affording clearance for the pivot pin of a mating coupler and having a horizontal portion affording a seat for the knuckle of said mating coupler, the connection of said device at its opposite ends affording limited rocking movement thereof, and a coil spring mounted on said pivot pin in compression between an end of said device and said coupler head.
30. In a car coupler, a coupler head having a guard arm with an opening therein, a transversely spaced pivot pin opposite said guard arm, a knuckle pivoted thereon, a rigid safety device positioned to underlie the knuckle of a mated coupler, said safety device being connected at one end to said pivot pin and having at its opposite end a hook-like member received in said opening, and resilient means between said coupler head and said safety device adjacent said pivot point, the connection of said device at its opposite ends affording limited rocking movement thereof to accommodate vertical angling between mated couplers equipped therewith.
35. EDMUND P. KINNE.
